DESIGN FOR A CURTAIN OR SIMILAR ARTICLE

Gustave F. Erhard, Scranton, Pa., assignor to The Scranton Lace Company, Scranton, Pa., a corporation of Pennsylvania

Application February 7, 1938, Serial No. 74,938

Term of patent 3½ years

To all whom it may concern:

Be it known that I, Gustave F. Erhard, a citizen of the United States, residing at 2015 N. Washington Avenue, in the city of Scranton, county of Lackawanna, and State of Pennsylvania, have invented a new, original, and ornamental Design for a Curtain or Similar Article, of which the following is a specification, reference being had to the accompanying drawing, forming a part thereof.

The drawing is a plan view of a curtain or similar article showing my new design.

The curtain which is made of open lace fabric is shown on a black surface to bring out the details thereof.

The characteristic feature of the design resides in the valance top in combination with the body of the curtain as shown.

I claim:

The ornamental design for a curtain or similar article as shown and described.

GUSTAVE F. ERHARD.
